UNITED STATES PATENT OFFICE

167,596

ELECTRIC SHAVER

Jan Streng, Ridgefield, Conn., assignor to Remington Rand Inc., New York, N. Y., a corporation of Delaware

Application February 29, 1952, Serial No. 18,721

Term of patent 14 years

(Cl. D22—3)

To all whom it may concern:

Be it known that Jan Streng, citizen of the United States, residing in the town of Ridgefield, State of Connecticut, has invented a new, original, and ornamental Design for an Electric Shaver, of which the following is a specification, reference being had to the accompanying drawing, forming a part hereof.

Fig. 1 is a top plan view of an electric shaver, showing my new design;

Fig. 2 is a side elevation thereof; and

Fig. 3 is an end elevation thereof.

I claim:

The ornamental design for an electric shaver, as shown.

JAN STRENG.
